SMOKE LIFTER FOR LOCOMOTIVES

James G. Blunt, Schenectady, N. Y., assignor to
American Locomotive Company, New York,
N. Y., a corporation of New York

Original application April 1, 1936, Serial No.
72,042. Divided and this application April 7,
1938, Serial No. 200,622

5 Claims. (Cl. 105—2)

This invention relates to a smoke lifter for a locomotive and more particularly for a streamline locomotive.

5 This application is a division of my application for Letters Patent for improvements in Streamline locomotive, filed April 1, 1936, Serial No. 72,042, Patent No. 2,177,590, issued October 24, 1939.

An object of the present invention is to provide a smoke lifter for a steam locomotive, comprising novel characteristics including an air passage for conveying air which, on leaving the passage, operates to aid in lifting the smoke coming from the smokestack away from the locomotive.

10 15 A further object is to provide a smoke lifter of the aforesaid characteristics having an exterior streamline surface forming a part of the streamline shroud of the locomotive.

20 A further object is to provide a smoke lifter of the aforesaid characteristics having the interior defining walls of its air passage streamlined.

25 Other objects of and advantages achieved by this invention will be apparent from the following description when considered in connection with the accompanying drawings which illustrate a preferred embodiment of the invention.

The invention is illustrated in the accompanying drawings in which only sufficient of the parts 30 of the locomotive are shown to afford a clear understanding of the invention and wherein Figure 1 is a diagrammatic side elevation of a streamline locomotive involving the present invention; Fig. 2 is an enlarged side elevation of the front portion of the locomotive shown in Fig. 1; Fig. 3, at the right, is a front view of the left half of the locomotive, and, at the left, is a section of the right half of the locomotive, on the line III—III of Fig. 2; and Figs. 4 to 8 are fragmental views, still further enlarged, of the locomotive showing the smoke lifter of the present invention, Fig. 4 being a partial plan of the forward portion of the locomotive showing the smoke lifter, Fig. 5 a section on the line V—V of Fig. 4, Fig. 6 a front end view of the parts shown in Fig. 4, Fig. 7 a section on the line VII—VII of Fig. 5, and Fig. 8 a section on the line VIII—VIII of Fig. 5.

55 Referring in detail to the drawings, a streamline locomotive is indicated generally by the reference numeral 1, and as it is sufficiently described in my co-pending application above referred to, a brief description herein is deemed sufficient. The locomotive, as shown, includes a streamline shroud 2 which for convenience may

be considered as comprising a front portion 3 extending around the front portion of the smokebox 4, an intermediate portion 5 covering the major portion of the boiler 6, and a cab portion 7. The portion of the shroud covering the top of the locomotive is substantially horizontal and free from obstructions. The shroud is formed of removable plates 8 held in place by bands 9 and by framework ribs disposed opposite each band and inside of the shroud, the first two ribs only being shown and indicated by the reference numeral 9a.

The smoke lifter, denoted generally by the reference numeral 10, may, if desired, be constructed as a separate feature, and then assembled with the locomotive. The forward end of the smoke lifter is covered by a streamline covering or shroud portion 11, later to be more fully described, which forms the top part of the shroud front portion 3. The remainder of the front portion 3 consists of the doors 12, later to be more fully described, and an extension of the lower part of the main locomotive shroud including a streamline pilot. The smoke lifter to the rear of the shroud portion 11, is covered by the adjacent plates 8. These plates are removable from the smoke lifter and are held in place by the bands 9 and by other means (not shown) in a manner fully described in my before-mentioned co-pending application and it is therefore not deemed necessary to repeat the description herein.

The smoke lifter is disposed around the smokestack 13 of the locomotive and extends from a point *a* somewhat to the rear of the smokestack 13 forwardly to the foremost rib 9a, this portion of the lifter being within the shroud portion 5, and forwardly therefrom to the point *b*. It comprises at each side an air passage 14, these passages meeting (but not communicating) at the rear of the smokestack, as will later more fully appear, and being entirely separated from each other forward of the smokestack by a centrally disposed structure 15. The smoke lifter 10 is disposed around the upper forward portion of the smokebox, this portion of the smokebox being denoted by the reference numeral 16.

The forward part of the lifter, that is to say the part in advance of the foremost rib 9a, comprises a bottom horizontal wall 17 which is straight along its rear edge to engage the front wall of the smokebox to which it is secured by the angle iron 18. The wall 17 extends beyond the smokebox at each side and, at these extended portions, extends rearwardly of the front wall of 55

the smokebox, these rearwardly extending portions being secured to the foremost rib 9a by brackets 19.

The wall 17 is adjacent the upper edges of the doors 12. There is a door on each side of the front vertical center line of the locomotive, and each door is hinged respectively to the foremost frame rib 9a by hinges 20, and secured to each other in closed position, where they meet at the front vertical center line, by aligned orificed lugs 21 which engage securing bolts. The doors are curved and are inclined upwardly and inwardly to effect a streamlining of the front of the locomotive. The front and side edges of the wall 17 are curved similarly to the curvature of these doors at their upper edges, so that the doors make a tight fit about these edges of this wall. The shroud portion 11, constituting the front, top and sides of this forward part of the smoke lifter, is shaped to somewhat resemble a section of a dome, the rear edge being secured to the foremost rib 9a and curved to form a flush joint with the adjacent part of the shroud portion 5 to maintain the streamline effect therebetween, and the bottom edge being secured to the bottom wall 17 and being curved to conform to the curvature of the front and side edges of said bottom wall 17 to form a flush joint with the doors 12 to maintain the streamline effect therebetween.

At each side of the centrally disposed structure 15 the shroud portion 11 is provided with a relatively large opening 22, which openings serve as inlets for the air to each of the respective air passages 14. These openings preferably extend from the sides of the structure 15 to substantially the sides of the dome-like wall, that is to say they include substantially the entire front of the dome-like wall at each side of the structure 15. Each of the openings is slatted and the slats 23 thereof extend entirely across the opening. The slats are curved at their forward edges by curvatures, corresponding to the curvature of the shroud portion 11, where located, their rear edges being respectively similarly curved. The planes of the slats are substantially parallel and slightly curved and tilted from the structure 15 upwardly. The forwards ends of the slats are adjacent the structure 15 and their rear ends are near the rear edge of the shroud portion 11. The slats are spaced one from the other. The bottom and top edges of each opening are substantially parallel to and spaced from their adjacent slats. The slats serve to divide the air entering an air passage 14 into suitably directed layers to enable the device to best serve as a smoke lifter.

The smokebox portion 16, which is involved in the description relating to the smoke lifter, comprises a front wall 24 which is the upper part of the front of the smokebox and which extends from the wall 17 to the top of the smokebox, and the cylindrical wall 25 which constitutes the top and sides of the portion 16 and which is inclined at its lower defining lines on each side of the portion 16 from the adjacent corner of the front wall 24 upwardly and rearwardly along lines following the contour of the cylindrical wall of the smokebox, one of these lines being shown at 26, and the other being oppositely disposed on the opposite side of the smokebox, to a point c at the top of the smokebox to the rear of the smokestack, where the two lines meet at the longitudinal center line of the top of the smokebox.

The smokestack 13 is formed as an integral

casting and the smokestack proper is of usual shape, passing downwardly through an opening in the shroud portion 5, and downwardly through the cylindrical wall 25 of the smokebox portion 16, and into the smokebox, in the usual manner.

The casting of the smokestack 13 is provided with an encircling flange 27 which is shaped to conform to the cylindrical smokebox, the marginal edges of the opening in the smokebox surrounding the smokestack extending beneath and being secured to this flange. The rear edge 28 of the flange is in a plane transverse of the smokebox. The edges 29 extend horizontally forwardly from the rear edge 28, and then turn inwardly and extend upwardly substantially parallel to the edge 28 for substantial distances, and then forwardly in curved lines around the forward part of the smokestack, meeting at the front of the smokestack at the longitudinal center line thereof. Integral with the rear portion of the flange are two aligned steam pipes or passageways 30. The passageways have substantially horizontal portions which extend in directions transverse of the smokebox. They extend through the flange 27, the inner ends of these portions being below the flange and the outer ends being above the flange and the top faces of these outer ends are extended forwardly and rearwardly beyond the passageways and from the rear end downwardly in a forward direction forming an inclined surface indicated at n, best shown in Fig. 5. In practice the outer ends 31 of the passageways are extended through the smokebox to the exterior, the smokebox being cut away to provide for this, and are connected with steam pipes leading from steam exhausts of locomotive auxiliaries. The passageways extend from their outer ends 31 transversely of the smokebox and, when reaching a point near the longitudinal center line of the smokebox, are directed upwardly, terminating at, or slightly below, the top of the smokestack. These upwardly directed portions are disposed adjacent to each other and to the rear portion of the smokestack, and their rear walls are streamlined, as best shown in Fig. 4. The casting is further provided with forwardly projecting spaced lugs 32 disposed well toward the sides of the smokestack for a purpose presently to appear.

The structure 15 comprises two vertical side walls 33 which are secured at their rear edges to the respective lugs 32, the portion of the smokestack between these lugs constituting the rearmost portion of the rear wall of the structure 15. The side walls 33 extend forwardly, in a direction longitudinally of the lifter, between the smokebox cylindrical wall and shroud portions 5 and 11 to the points d at the tops and to the front of the smokebox at the bottoms, the shroud portions and the smokebox cylindrical wall between these side walls, as thus far described, constituting respectively the rearmost portions of the top and bottom walls of the structure 15. The side walls then extend downwardly, the rear edges of the downwardly extending portions being adjacent to the front wall 24 and extending to the wall 17, the wall 24 between the side walls 33 thus constituting the remaining or lower portion of the rear wall of the structure 15. The lower edges of the side walls 33 then extend forwardly along and adjacent to the wall 17 to the forward edge of this wall 17, the portion of this wall 17 between the side walls 33 thus constituting the remaining or front por-

tion of the bottom wall of the structure 15. The top edges of the side walls 33 extend forwardly and downwardly from the points *d* along and adjacent to the curved outer wall of the shroud portion 11 to points indicated at *e*, the top edges of the side walls being suitably curved corresponding to the curvature of the shroud portion 11. The edges of the side walls 33 extend horizontally forwardly from the points *e* to points *f* substantially vertically above the front edge of the wall 17 and the front edges of these side walls 33 extend vertically downwardly from the points *f* to the wall 17.

The shroud portion 11 is cut away, as will presently appear, and with this in mind, it is noted that, as thus far described, the structure 15 is open at the front and also open at the top of the front portion. This front portion is closed by a wall 34 of somewhat dome or arch shape, the front edge of which is in line with the front edges of the side walls 33, and extends on either side to the points *f*, the bottom edges of which extend rearwardly from the points *f* to the points *e* adjacent the edges of the side walls 33 between these points, and make a flush joint therewith the side walls, the top of which extends from the front edge horizontally rearwardly in line with the top edge of the shroud portion 5 until it meets the top of the shroud portion 11 at the point *d'*, the edges of which, between the two points *e* and the point *d'*, are adjacent the shroud portion 11 and being suitably curved to conform to the curvature thereof, as shown in Fig. 5, the shroud portion 11 being cut away along these lines of contact, and the lines of contact with the walls 33, as indicated approximately by the lines 35, Fig. 4, which extend from the point *d'* to the wall 17. The wall 34 and the shroud portion 11 between the side walls 33 and the wall 34 constitute the remaining portion of the top wall of the structure 15, and the opening at the front of this structure, defined by the forward edges of the side walls 33, the forward curved edge of the wall 34 and the front edge of the wall 17 between the side walls 33, is closed by a wall 36 of a contour similar to the contour of said opening.

A shelf 37 is secured to the side walls 33 near the forward ends thereof for the reception of a horn (not shown), the mouth of which will extend in practice through an opening 38 formed in the top portion of the wall 36. A head lamp (not shown) for the locomotive may be secured to the wall 36 below the opening 38 in any manner desired.

From the foregoing description of the centrally disposed structure 15 it will be noted that the structure forms a dead space separating the two air passages 14 and is entirely enclosed except that the wall 17 between the side walls 33 is provided with a large opening 39 affording communication between the space within the structure 15 and the space to the rear of the doors 12. The side walls 33 are disposed approximately in line with the sides of the smokestack so that the exterior of the smokestack will not obstruct the free passage of the air through the passages 14, presently to be described.

The passages 14 are similar in all respects and therefore a description of one will be sufficient. The rear portion of the lifter, that is to say the portion to the rear of the smokestack, is divided at the longitudinal center into halves, as will later be described, each half constituting the rear portion of the passage 14 on its side of the lifter. Bearing this in mind, this rear portion will be

described, for the present, as if it were a single curved passageway. This passageway is denoted by the reference numeral 40, and extends in general direction transversely of the locomotive and has open ends, and an open top preferably just below the top of the smokestack, that is to say in line with the top of the shroud portion 5, the top of this rear portion or passageway being slightly curved, that is to say suitably shaped to conform to the shape of the corresponding portion of the top of the shroud portion 5. The rear walls of the vertical portions of the steam pipes 30, together with small sections of the smokestack adjacent the outer ends of these rear walls and extending to the adjacent shroud supports 41 provide a wall 42 serving as a forward wall of the curved passageway 40. The supports 41 form part of the smoke lifter although they may be employed in a streamline locomotive such as that of said aforementioned application Serial No. 72,042 for supporting other features of the locomotive, and reference may be had to said application for a fuller description of these features. Suffice it to say, in connection with the present invention, that these supports 41 are connected at their inner ends to the smokestack by means of angle irons *m* and at their outer ends to the second of the frame ribs 9a, one being shown in Fig. 4.

The passageway 40, which is disposed between the shroud portion 5 and the top of the smokebox, further comprises a rear wall 43 having a vertical portion 44 which is shaped to conform to the shape or curvature of the adjacent part of the shroud portion 5 and is provided at its upper edge 35 with a rearwardly extending flange 45 which overlaps the adjacent margin of the shroud portion 5, a similarly shaped angle iron 46 being secured to the rear face of the wall portion 44 with its rearwardly extending leg adjacent the shroud portion 5 to afford a support for the shroud portion 5 at this location. The wall portion 44 is curved from the center in a forward direction on both sides and extends to the shroud supports 41, it being secured at each end to the adjacent shroud support 41. At the bottom edge of the portion 44 the rear wall 43 extends downwardly and forwardly, forming thereby an inclined portion 47 having its lower edge *o* curved from the center in a forward direction on both sides to the flange 27 in line with the shroud supports 41, the ends of this portion 47 and the portion 44 terminating in substantially vertical lines *p*, (see Fig. 8) extending from the respective shroud supports 41 to the bottom of the passages 14 for a purpose later to be mentioned. The passageway 40 is further provided with a bottom wall 48 which extends from the bottom edge of the wall portion 47 forwardly and downwardly until it meets the flange 27 and inclined top faces of the pipes 30 along a line shown approximately at *g*, Fig. 4. These inclined faces between the line *g*, the forward wall 42 and the ends of the passageway 40 serve as the remaining portion of the bottom of the passageway 40.

It will thus be seen that the passageway 40 is open at the top and is enclosed at its bottom and rear by walls that are curved or shaped to best conform the top of the passageway 40 to the shape or curvature of the shroud portion 5 and that at the bottom are straight across transversely of the lifter. The walls are further curved forwardly from each side of the longitudinal center line of the lifter, and furthermore are, in general direction, inclined upwardly from the 75

front rearwardly, which most efficiently directs the air entering the passageway 40 at the ends thereof upwardly through the open top for producing a maximum lifting effect to the smoke passing rearwardly from the smokestack as it engages the streams of air coming from the open top or mouth of the lifter.

To better provide for a maximum lifting result, the ends of the passageway 40 are made considerably wider than the middle so that the entering streams of air will be reduced in volume as they advance toward the center, and increased in intensity, thereby increasing their lifting capacity. To still better provide for this lifting capacity the passageway 40 is slatted throughout its open top by a row of suitably spaced vertical slats 49 extending longitudinally of the lifter. The upper edges of the slats are in substantially the same plane as the top of the passageway 40 (that is to say the top of the shroud portion 5) and extend downwardly for a short distance into the passageway 40. They are connected at their rear ends to the wall portion 44 and some of them at their forward ends are connected to the rear faces of the shroud supports 41 and the remainder of them are connected to a band 50 which is secured at its ends to the shroud supports 41 and is adjacent to and follows the contour of the wall 42, thereby maintaining the streamline effect at this location, all as shown in Figs. 4 and 5.

Instead of a centrally disposed slat, the wall 51 is substituted, which extends transversely throughout the passageway 40 and is secured at its rear and bottom ends to the wall portions 44 and 47 and to the wall 48. Its forward end is bolted to a flange 52 extending rearwardly from the rear wall of the vertical portions of the pipes 30. This wall 51 divides the passageway 40 so that there is no commingling within the lifter of the oppositely directed streams of air flowing therethrough from the opposite ends. The wall 51, through its connection with the flange 52, connects the rear of the smoke lifter with the locomotive.

As previously stated, while, for convenience, the rear portion of the smoke lifter has been described as if it were a single passageway, it actually comprises, due to the dividing wall 51, the two rear portions, indicated respectively by the reference numeral 53, of the two air passages 14. The forward portions 54 of these passages 14 are similar in all respects, and therefore a description of one will suffice.

Similar to the rear portion 53 the forward portion 54 from the front opening 22 is directed generally rearwardly and upwardly, and decreases in cross-sectional area from the cross section of largest area at the front portion to the cross section of smallest area at the rear end, this end being substantially the same in size and shape as the adjacent forward end of the respective portion 53, and the adjacent walls of the two portions 53 and 54 meeting in substantially flush joints, thereby obviating any obstruction to the smooth flow of air through the passage 14. In short, there are no obstructions in the passage 14 to offer any resistance to the air, and the walls of the passage are shaped and directed to obtain a maximum of smoke lifting effect at the outlet at the rear of the smokestack. This is further enhanced by the, generally speaking, converging walls characteristic of the passage 14 which acts to intensify the smoke lifting power of the air which rushes into the passage 14 through

its opening 22 as the locomotive moves forwardly.

The portion 54 of the passage 14 is completely enclosed by top, bottom and side walls, thereby confining all the air that enters through the opening 22 until it leaves the portion 54 at the rear end and enters the portion 53, from which it emerges at the top in rectangular columns provided by the slats 49, the length of these columns being directed longitudinally of the locomotive, which in actual practice has proven to provide a satisfactory lifting of the smoke to convey it, to a maximum extent, away from the top and sides of the locomotive and cars at the rear.

The walls defining the portion 54 are comprised of a wall 55 which is flat and relatively narrow. It preferably is straight across in a transverse direction, that is to say it has no inclination in this direction. Its forward end 56 is supported by the adjacent rearwardly extending portion of the wall 17 a little to the rear of the front wall of the smokebox, this end being slightly spaced from the adjacent part of the cylindrical wall of the smokebox. The wall 55 is inclined upwardly from its forward end rearwardly, and its outer and inner edges 57 and 58 respectively are inclined from their forward ends inwardly except that the edge 57, from its forward end, is directed longitudinally rearwardly, with no inclination inwardly, until it reaches the foremost rib 9a. The upward and inward inclinations of the wall 55 are such that its rear edge rests upon the portion 59 of the correspondingly inclined wall of the adjacent pipe 30, where the wall 55 meets the adjacent edge of the wall 48 which is similarly supported on the inclined wall of the adjacent pipe 30. The wall 55 is supported at various intermediate points by brackets 60 which are secured to the sides of the cylindrical wall of the smokebox, and the edge 58 is suitably shaped to follow the cylindrical wall of the smokebox in slightly spaced relation therewith and defines the bottom of the smokebox portion 16.

A curved wall 61 is similarly spaced from the cylindrical wall of the smokebox, and forms another portion of the forward portion 54 of the passage 14. It has its lower edge connected to the inner edge 58 of the wall 55, this edge of the wall 61 being suitably shaped for this purpose. The wall 61 from this edge is curved corresponding to the curvature of the cylindrical wall of the smokebox, and its upper or inner edge meets and is secured to the outer face of the adjacent side wall 33 of the structure 15 in slightly spaced relation from the cylindrical wall of the smokebox. The rear edge of the wall 61 meets and is secured, at its margin, to the flange 27. The forward edge 62 of the wall 61 is in substantial alignment with the forward end 56 of the wall 55, is disposed in a vertical plane transverse of the locomotive, and, as is obvious, is curved corresponding to the cylindrical wall of the smokebox, extending from the lowermost point of the wall 55, which is supported on the wall 17, at its lower or outer end *h*, to the adjacent side wall 33 at a point near the cylindrical wall of the smokebox, at its upper or inner end.

A wall 63 is disposed in the angle formed by the plane of the edge 62, the wall 17 and the adjacent wall 33. This wall 63 is curved and shaped somewhat like a quarter of a hollow cone, formed by cutting planes represented by the wall 17 and adjacent wall 33, with its apex *i* disposed in the angle formed by the meeting of the adjacent wall 75

33 with the wall 17, with its base *j* (which is the rear edge of the wall 63) engaging the edge 62, with the rectilineal element *k*, formed by one of the cutting planes (wall 17), constituting the bottom edge of the wall 63, and with the rectilineal element *l*, formed by the other of the cutting planes (adjacent wall 33), constituting the side edge of the wall 63.

It will be noted that the space within the section of the cone forming the wall 63 is closed and forms no part of the passage 14, the exterior of the wall 63 being for the purpose of streamlining the forward part of the passage 14 to permit a smooth flow of the air upon entering the passage,

15 or in other words it covers the included portion at the front of the smokebox which, due to its being directed transversely to the air flow, would, were it not for the wall 63, create a large resistance to the air entering the passage 14.

20 It will thus be seen that the bottom wall of the forward portion 54 of the passage 14 is composed of the walls 63, 61 and 55, that the wall 55 is inclined upwardly and inwardly from its front end to its rear end, that the wall 61, at its outer

25 (lower) edge is similarly inclined upwardly and inwardly, the wall 61 thereby gradually decreasing in width from the front end to the rear end, and also that the walls 55 and 61, at their upper edges, meet the pipe wall 59 and flange 27 respectively as aforesaid, the wall 48 likewise, as aforesaid, meeting the pipe wall and flange. The parts at this location combine to form a smooth even surface which offers no obstruction to the air passing through the passage 14.

30 A curved wall 64 forms the top wall of the forward portion 54 of the passage 14. This wall 64, at its forward edge 65, follows the curvature of the adjacent curved wall of the shroud portion 11, and engages this shroud portion 11. Its inner

40 (upper) side edge 66 engages the adjacent wall 33 near the top thereof, and extends at its rear around the adjacent portion of the smokestack, and is secured thereto by an angle iron 67. The rear end 68 of the wall 64 extends under the adjacent shroud support 41 to which it is secured,

45 thereby locating the top of the portion 54 of the passage 14 at its rear end substantially on a line with the bottom edges of the slats 49. The wall 64 is curved outwardly and downwardly

50 from its inner (upper) edge in a manner to provide the required cross-sectional areas for this forward portion 54 of the passage 14, until it reaches a line vertically above the edge 57 of the wall 55, at which location it extends downwardly

55 substantially vertically and inwardly from the front to the rear, meeting at its bottom edge the edge 57, the rear edge of this vertical portion of the wall 64 meeting the adjacent end edges of the wall portions 44 and 47.

60 It will thus be seen that the top wall of the passage 14 comprises the wall 64 and the adjacent portion of the shroud portion 11. It will further be seen that the forward portion 54 of the passage

65 14 is disposed entirely beneath the shroud portions 5 and 11 and that the passage 14 is entirely enclosed except at its front and rear ends.

While some of the brackets and angle irons employed in securing the various parts have been referred to, it will be appreciated that such, or other appropriate means, including welding, are employed to secure the various parts together, as found necessary. Furthermore, as previously stated, the smoke lifter may be made as a separate structure, and then assembled with and se-

cured to the various appropriate parts of the locomotive and shroud portions.

While the invention has been illustrated in the foregoing description in a streamline locomotive of preferred construction, it will be understood that many and various changes and modifications in form, arrangement of parts and details of construction thereof may be made, and that all such changes and modifications as fall within the scope of the appended claims are contemplated as a part of this invention.

The invention claimed and desired to be secured by Letters Patent is:

1. In a locomotive, the combination of a smokebox; a smokestack projecting upwardly from the top of said smokebox and spaced rearwardly from the front thereof; a streamline covering surrounding the top, sides and front of a forward upper portion of said smokebox and separated therefrom to provide an intervening space, said smokestack opening through the top of said covering; means closing said space to provide a passageway disposed centrally of said portion and extending in a direction longitudinally of said locomotive from the front of said covering to a point spaced rearwardly from the rear of said smokestack for the passage of air through said closed space; and a partition extending longitudinally of said passageway and disposed centrally relative thereto and being adjacent to and extending from the front of said smokestack forwardly to the front of said covering and downwardly between said front of said covering and said front of said smokebox to the bottom of said smokebox portion, dividing said passageway adjacent thereto into two substantially equal sections, each being disposed at least in part opposite the portion of said front of said smokebox portion at the corresponding side of said locomotive and being open through said front of said covering providing an opening for the admission of air, and said sections being open through said covering at the rear of said smokestack for the emission of said air, each of said sections being in part adjacent a side of said smokestack.

2. In a locomotive, the combination of a smokebox; a smokestack projecting upwardly from the top of said smokebox and spaced rearwardly from the front thereof; a streamline covering surrounding the top, sides and front of a forward upper portion of said smokebox and removed therefrom to provide an intervening space, said smokestack opening through the top of said covering; means closing said space to provide a passageway disposed centrally of said portion and extending in a direction longitudinally of said locomotive from the front of said covering to a point spaced rearwardly from the rear of said smokestack for the passage of air through said closed space; a partition extending longitudinally of said passageway and disposed centrally relative thereto and being adjacent to and extending from the front of said smokestack forwardly to the front of said covering and downwardly between said front of said covering and said front of said smokebox to the bottom of said front of said smokebox portion, dividing said passageway adjacent thereto into two substantially equal sections, each section being open through said front of said covering providing an opening for the admission of air, each said opening being disposed at least in part opposite the part of said front of said smokebox portion at the corresponding side of said partition and said sections being

open through said covering at the rear of said smokestack for the emission of said air, each of said sections being in part adjacent a side of said smokestack; and a covering disposed in each 5 of said sections adjacent said partition, each enclosing and adjacent its correlated part of said front of said smokebox portion, extending forwardly therefrom in streamlined contour to offer minimum resistance to air entering said opening 10 adjacent thereto.

3. In a locomotive, the combination of a smokebox; a smokestack projecting upwardly from the top of said smokebox and spaced rearwardly from the front thereof; a streamline covering 15 rounding the top, sides and front of a forward upper portion of said smokebox and removed therefrom to provide an intervening space, said smokestack opening through the top of said covering; means closing said space to provide a 20 passageway disposed centrally of said portion and extending in a direction longitudinally of said locomotive from the front of said covering to a point spaced rearwardly from the rear of said smokestack for the passage of air through said 25 closed space, said means including a wall at each side of said smokebox portion between said smokebox portion and the adjacent side of said covering providing bottom walls for said passageway; and a partition extending longitudinally of 30 said passageway and disposed centrally relative thereto, comprising a part disposed to the rear of said smokestack and a part disposed adjacent to and extending from the front of said smokestack forwardly to the front of said covering and down- 35 wardly between said front of said covering and said front of said smokebox to the bottom of said front of said smokebox portion, said partition dividing said passageway into two substantially equal sections, each being disposed at least 40 in part opposite the portion of said front of said smokebox portion at the corresponding side of said locomotive and being open through said front of said covering providing an opening for the admission of air, and open through said covering at the rear of said smokestack for the emission 45 of said air, each of said sections being in part adjacent a side of said smokestack.

4. In a locomotive, the combination of a smokebox; a smokestack projecting upwardly from the top of said smokebox and spaced rearwardly from the front thereof; a streamline covering 50 surrounding the top, sides and front of a forward upper portion of said smokebox and removed therefrom to provide an intervening space, said smokestack opening through the top of said covering; means closing said space to provide a 55 passageway disposed centrally of said portion and extending in a direction longitudinally of said locomotive from the front of said covering to a point spaced rearwardly from the rear of said smokestack for the passage of air through said 60 closed space; box-like means closed against admission of currents of air from the outside of

said locomotive extending longitudinally of said passageway and disposed centrally relative thereto and being adjacent to and extending from the front of said smokestack forwardly to the front of said covering dividing said passageway adjacent thereto into two substantially equal sections, said front of said covering being open providing inlet means for the admission of air to said sections, said inlet means being disposed at least in part opposite said front of said smokebox portion, and said sections being open through said covering at the rear of said smokestack for the emission of said air, each of said sections being in part adjacent a side of said smokestack; and covering means disposed in said closed space 15 enclosing and adjacent said front of said smokebox portion opposite said inlet means, extending forward from said smokebox portion in streamlined contour to offer minimum resistance to air 20 entering said inlet means. 20

5. In a locomotive, the combination of a smokebox; a smokestack projecting upwardly from the top of said smokebox and spaced rearwardly from the front thereof; a streamline covering 25 surrounding the top, sides and front of a forward upper portion of said smokebox and removed therefrom to provide an intervening space, said smokestack opening through the top of said covering; means closing said space to provide a passageway disposed centrally of said portion and 30 extending in a direction longitudinally of said locomotive from the front of said covering to a point spaced rearwardly from the rear of said smokestack for the passage of air through said closed space; box-like means enclosed against admission of currents of air from the outside of said locomotive extending longitudinally of said passageway and disposed centrally relative thereto and being adjacent to and extending from the front of said smokestack forwardly to the front 40 of said covering and downwardly between said front of said covering and said front of said smokebox to the bottom of said front of said smokebox portion, dividing said passageway adjacent thereto into two substantially equal sections, each section being open through said front of said covering providing an opening for the admission of air, each said opening being disposed at least in part opposite the part of said front of said smokebox portion at the corresponding 45 side of said box-like means, and said sections being open through said covering at the rear of said smokestack for the emission of said air, each of said sections being in part adjacent a side of said smokestack; and a covering disposed in each 50 of said sections adjacent said box-like means, each enclosing and adjacent its correlated part of said front of said smokebox portion, extending forwardly therefrom in streamlined contour to offer minimum resistance to air entering said 60 opening adjacent thereto. 55
